VAPOR LAMP

Daniel S. Gustin, Bloomfield, N. J., assignor, by
mesne assignments, to Westinghouse Electric
and Manufacturing Company, East Pittsburgh,
Pa., a corporation of Pennsylvania

Application October 20, 1934, Serial No. 749,197

3 Claims. (Cl. 176—122)

This invention relates to a discharge device of the type employing an incandescent cathode and solid electrodes operating in an ionizable medium and, more particularly, to devices operating in a medium comprising a metallic vapor.

In devices of the character to which the present invention relates, it has been the practice to use a metallic vapor such as sodium or the like, together with a small amount of a rare gas such as argon or neon to promote starting. A device of this character is shown and described in co-pending application Serial Number 668,506 filed April 29, 1933, and assigned to the present assignee.

15 Metallic vapor lamps, particularly the sodium vapor lamp, has found considerable use in connection with highway lighting where the lamps are operated in series with a constant current supply. It is well known that sodium to be efficiently operative must be maintained at a temperature of between 200° to 300° centigrade and when lamps of the above character are used for outdoor lighting, the variation in the temperatures to which they are subjected causes a variation in the operation of the device. If the temperature falls too low the vapor condenses, often causing a termination of the discharge.

It is an object of the present invention to provide a lamp of the above character with means for maintaining the lamp at operating temperature.

Another object of the invention is to provide a discharge lamp of the metallic vapor type in which current flowing through the discharge is utilized to heat the vapor.

Another object of the invention is to provide a discharge device of the above character in which the internal circuit includes a heater element in parallel with current flowing through the discharge.

Another object of the invention is to provide a discharge device including a plurality of anodes and a cathode and resistant heaters in series with the cathode and anodes.

45 Other objects and advantages of the invention will be more readily understood by reference to the accompanying drawing in which

Fig. 1 is a side elevational view of a device constructed in accordance with the present invention, the bulb portion being shown in cross section;

Fig. 2 is a vertical sectional view on the line II—II of Fig. 1, in the direction of the arrows, showing the anodes, cathodes and resistance elements;

Fig. 3 is a sectional view taken on line III—III in Fig. 1, in the direction of the arrows;

Fig. 4 is a view showing the same general construction as that shown in Fig. 1 but includes a center tap on the cathode connecting with a 5 transformer for the purpose of including a choke coil as shown diagrammatically together with the transformer.

Although the present invention may be employed in various forms of discharge devices, the 10 selected embodiment of the invention comprises a bulb 10 having a neck portion 11 arranged to fit a flare tube 12 integral with an outer bulb or chamber 13.

A clamping ring 14 is employed in conjunction 15 with a resilient collar 15 to hold the bulb 10 in position. The flare tube 12 may be provided with the usual press 16 and exhaust tube 17. Extending from the press are support rods 18 and 19 connected to the terminals of a cathode 21. The 20 cathode may be in the form of a helical coil comprised of the tungsten or other refractory metal and may have a coating of electron emissive material sprayed or otherwise deposited thereon. The electron emissive material may be a mixture of carbonates in the usual nitro-cellulose amyl acetate binder. A coating of barium oxide has been found satisfactory. The coil 21 may be provided with a core of barium silicate instead of the coating material or both may be used. 25

Lead wires 22 and 23 extend through the press and are electrically connected with conductive support members 24 and 25 respectively. Electrically connected with the conductor 24 is an anode 26 in the form of a hollow cylinder disposed 30 at the lower end of the bulb and preferably coaxial therewith. Electrically connected to an end of the support 25 is a similar anode 27 disposed at the other end of the bulb and preferably coaxial with the anode 26. An insulative 35 sleeve 28 may be employed to enclose the conductive support 25. Between one terminal of the cathode 21 and the anode 26 is connected a resistance element 29 and between the other terminal of the cathode and the anode 27 is connected a resistance element 31. The elements 29 and 31 40 may be in the form of helical coils of refractory material such as tungsten and of suitable proportions as give the desired resistance, so that when a discharge occurs most of the current will take the path of the discharge. The adjacent ends of the elements 29 and 31 are desirably respectively connected to diagonal extensions on the rods 18 and 19, whereby they are properly spaced 45 from the cathode 21. Thus said elements are 50

55

Fig. 2 is a vertical sectional view on the line II—II of Fig. 1, in the direction of the arrows, showing the anodes, cathodes and resistance elements;

Fig. 3 is a side elevational view of a device constructed in accordance with the present invention, the bulb portion being shown in cross section;

Fig. 4 is a view showing the same general construction as that shown in Fig. 1 but includes a center tap on the cathode connecting with a 5 transformer for the purpose of including a choke coil as shown diagrammatically together with the transformer.

Although the present invention may be employed in various forms of discharge devices, the 10 selected embodiment of the invention comprises a bulb 10 having a neck portion 11 arranged to fit a flare tube 12 integral with an outer bulb or chamber 13.

A clamping ring 14 is employed in conjunction 15 with a resilient collar 15 to hold the bulb 10 in position. The flare tube 12 may be provided with the usual press 16 and exhaust tube 17. Extending from the press are support rods 18 and 19 connected to the terminals of a cathode 21. The 20 cathode may be in the form of a helical coil comprised of the tungsten or other refractory metal and may have a coating of electron emissive material sprayed or otherwise deposited thereon. The electron emissive material may be a mixture of carbonates in the usual nitro-cellulose amyl acetate binder. A coating of barium oxide has been found satisfactory. The coil 21 may be provided with a core of barium silicate instead of the coating material or both may be used. 25

Lead wires 22 and 23 extend through the press and are electrically connected with conductive support members 24 and 25 respectively. Electrically connected with the conductor 24 is an anode 26 in the form of a hollow cylinder disposed 30 at the lower end of the bulb and preferably coaxial therewith. Electrically connected to an end of the support 25 is a similar anode 27 disposed at the other end of the bulb and preferably coaxial with the anode 26. An insulative 35 sleeve 28 may be employed to enclose the conductive support 25. Between one terminal of the cathode 21 and the anode 26 is connected a resistance element 29 and between the other terminal of the cathode and the anode 27 is connected a resistance element 31. The elements 29 and 31 40 may be in the form of helical coils of refractory material such as tungsten and of suitable proportions as give the desired resistance, so that when a discharge occurs most of the current will take the path of the discharge. The adjacent ends of the elements 29 and 31 are desirably respectively connected to diagonal extensions on the rods 18 and 19, whereby they are properly spaced 45 from the cathode 21. Thus said elements are 50

55

brought into a common axial plane and maintained substantially parallel to one another, while angularly disposed with respect to the bulb axis. A disk 32 of asbestos or other suitable material is disposed in the neck portion of the bulb 10 to keep the vapor from contact with the cool portion of the stem.

5 A lamp constructed, as described above, may be provided with the usual screw threaded base 10 to which the lead wires 22 and 23 may be connected in the manner employed for standard lamps.

When in operation current normally flows through lead 22, resistance element 29, cathode 21, resistance element 31 and back through lead 23. The bulb 10 may have deposited therein a quantity of vaporizable metal such as sodium or cadmium and a small amount of rare gas. When current flows through the heater elements, which 15 are of relatively high resistance, they become heated and the cathode being in series with the heater elements is also heated to an electron emitting temperature. By reason of the rare gas content, an initial discharge is caused in the rare 20 gas which, together with the heater elements operate to vaporize the sodium or other material creating a vapor which becomes ionized. This results in an appreciable discharge between one 25 anode and the cathode during the opposite cycle, when the lamp is operated on alternating current. As the discharge increases, the cathode is heated 30 by bombardment and reaches a temperature at which it becomes highly electron emissive. When the device is in full operation, the main current 35 flow is through the discharge by reason of the resistance heater elements.

Although the heater elements take sufficient current to maintain them at a temperature sufficient to keep the sodium from condensing at low 40 temperatures, they do not, however, pass sufficient current to reduce the discharge current flow to the point at which it would not be effective to keep the lamp operating at the required lumens per watt.

45 For the purpose of smoothing out the alternating current, the cathode 21 may, as shown in Fig. 4, have a central connection 33 in the form of a conductor 34 which connects with one end of the choke coil or condenser 35, the opposite end 50 of which connects with a central tap 36 on the secondary 37 of a transformer 38. With the construction as shown in Fig. 4, the operation of the lamp is less subject to flicker.

Although the present device may be used on 55 commercial lines for series burning where a constant current supply is provided, it is obvious that it may also be used on suitable line voltage with a

given current and that a suitable ballast resistance or other current regulating means may be employed.

A preferred embodiment of the invention is shown and described herein, but it is to be understood that modifications may be made therein without departing from the spirit and scope of the appended claims.

I claim:

1. In combination with an electrical discharge device comprising an elongated bulb, an anode in said bulb at each end, a cathode disposed between said anodes, and heating means electrically connecting said cathode and anodes, of means for energizing said device comprising a transformer the secondary terminals of which are connected to said anodes, and stabilizing means, one terminal of which is connected to a central tap on said secondary, and the other terminal of which is connected to a central point of said cathode, for minimizing flicker of said device.

10 15 20 25 30 35 40 45 50 55 60 65 70 75 80 85 90 95 100

2. An electrical discharge device comprising a bulb, a quantity of sodium in said bulb, a hollow cylindrical anode disposed adjacent each end of said bulb, said anodes being axially disposed with respect to one another, a thermionically active cathode formed as a helix of wire coated with electron emission material, disposed substantially midway between and with its axis extending transverse to the axis of said anodes, means extending from one end of said bulb for supporting said anodes and cathode, said anode supporting means serving to conduct current thereto, and a helical wire coil electrically connected to the cathode and each anode and extending therebetween to conduct current to said cathode from said anodes, to heat the former to electron emitting temperature, and maintain the sodium vaporized to a sufficient extent under varying conditions of operation.

3. A discharge device comprising a bulb, a cathode, a pair of anodes disposed substantially coaxial with one another, one on each side of said cathode, a support for each end of the cathode, a lead extending to each anode, a resistance heater element extending along the discharge path between each anode and the cathode, said heater elements lying approximately in a plane axial of the anodes, the anode-adjacent end of each element being disposed approximately axial of its anode and electrically connected thereto, the cathode-adjacent ends of the elements being laterally spaced from each other and said cathode, and connected to extensions from the cathode and supports.
